UNITED STATES PATENT OFFICE.

RANDOLPH H. ALMIROTY, OF NEW YORK, N. Y.

SEALING MEANS FOR BURIAL-CASKETS, &c.

1,306,457.

Specification of Letters Patent. Patented June 10, 1919.

Application filed December 26, 1918. Serial No. 268,237.

To all whom it may concern:

Be it known that I, RANDOLPH H. ALMIROTY, a citizen of the United States, and a resident of the borough of Manhattan, city, 5 county, and State of New York, have invented certain new and useful Improvements in Sealing Means for Burial-Caskets, &c., of which the following is a specification.

While applicable to analogous uses, my invention is designed more particularly to afford an automatically locking and hermetically sealing device especially adapted for use as a means of closure for burial caskets. The invention consists essentially in forming the rim of the casket with a continuous circumscribing mortise groove having a relatively narrow entrance in conjunction with a coincident continuous circumscribing shouldered tenon on the cover adapted to be 10 positioned in said mortise groove in the rim of the casket when the cover is applied to the latter and to be embedded and rigidly secured therein by means of a waterproof sealing compound substantially as hereinabove set forth, whereby a hermetically sealed joint is effected between the parts which is practically indestructible, in that a rigid, integral, unitary structure is attained.

In the accompanying drawings, Figure 1, is a sectional projection of a simple form of casket made in accordance with my invention;

Fig. 2, is a sectional detail on a larger scale showing the parts of the joint before copulation;

Fig. 3, is a like view, showing the copulation of the parts and the completion of the seal;

Figs. 4 and 5, are diagrams illustrating variations in the cross sections of the mortise groove.

B, represents the body portion of a casket of plain design, the rim b, of which is formed in accordance with my invention, i. e., 45 with a continuous circumscribing mortise-groove m, extending around both the sides and ends of the body. This mortise groove m, opens through the top of the rim, the opening or mouth m', being of less width 50 than the cross area of the groove m, below. By preference the width of the mouth or opening m', of the mortise-groove m, is but slightly greater than the width of the lateral extension c, on the lower portion of the 55 coupling flange or tenon c', which is protuberant from the under side of the edge c², of

the lid or cover C,—only sufficient margin of width being provided in the entrance m', to said mortise-groove m, to admit of the insertion of said coupling tenon c', when the 60 lid C, is applied to body B, of the casket.

In other words the mouth of the mortise-groove is undercut and of increased area in cross section, so as to afford ample space for a suitable quantity of sealing compound s. 65 The lid C, is formed with an external circumscribing register flange c'', which fits the rim b, of the casket body B, and thereby centralizes the coupling tenon c, c', with relation to the mortise-groove m. 70

The contacting faces of the flange and rim are correspondingly beveled, as shown, so that when the lid is placed down in position a wedge action is produced that tends to draw the parts together and form a tight 75 joint.

A preferred configuration of mortise-groove m, is shown in the first three figures of the drawing, although I do not restrict myself thereto, nor to any specific shape 80 thereof except that the entrance to the groove m, must be contracted as related to the portion of the groove below to form in-turned shoulders m^x, m^x, which confine and prevent the withdrawal of the mass of sealing compound s, when set. Thus in the modification shown diagrammatically in Fig. 4, which is only one of many that might be resorted to with like result, the upper side walls of the groove m, simply converge upward and inward centrally to the mouth m', of the mortise-groove m, forming nevertheless suitable retaining shoulders m^x, m^x, which lock the mass of cement s, permanently in position when set, as before stated. 90 In the configuration of cross section of mortise groove m, shown in the first three figures of the drawings, one or the other of the shoulders m^x, guarding the mouth or opening m', into the said mortise-groove m, is 100 made of less depth than the other to facilitate the insertion of the flukes c, and shank c', of the coupling tenon on the lid C, (when the latter is applied) by providing for the flow upward and outward of the surplus of 105 semi-liquid sealing compound s, displaced by said coupling tenon c, c', as positioned in said groove m.

The shape of the coupling tenon c, c', in cross section is also obviously of secondary 110 importance provided it is adapted to perform the function of an anchor or locking

means when embedded in the hardened sealing compound. Thus, any suitable lateral flaring, extension, or enlargement of the lower portion of the shank c' , of the tenon 5 that will afford adequate fluke surface adapted to insure a firm and rigid hold of the coupling tenon in and to the hardened cement s , in which it is embedded, will answer the purpose,—the positive and permanent 10 union of the congealed cement s , and of the coupling tenon c, c' , thus anchored therein resulting in a sealed joint between casket body and lid that is practically indestructible in that the joint is as strong, if not stronger, 15 than any other portion of the unitary structure thus attained.

In the modification shown in Fig. 5, the fluke extension c , protrudes on one side only of the shank c' , of the coupling tenon, and 20 the mouth of the mortise-groove m , is formed with only one opposed retaining shoulder m^* , but it is obvious that a like result may be attained also by this configuration of interlocking parts. 25 The area and capacity of the mortise-groove m , as related to the size and displacement of the coupling tenon c, c' , is such as to accommodate a quantity of sealing compound slightly in excess of that required to fill the 30 groove when said coupling tongue is positioned therein, so that sufficient of such sealing compound will be forced out of the said groove and between the opposed surfaces of lid and cover adjacent thereto to insure the 35 hermetical sealing of the joint as a whole when the cement has set and hardened.

It is to be understood that the sealing compound s , when introduced into the mortise-groove m , prior to the sealing operation 40 is substantially of the consistency of heavy cream, so that it will flow readily and be readily displaced in part to fill the interstices incident to the contactual surfaces between lid and casket rim, thereby hermetically sealing the joint between said surfaces. 45

While I do not claim the use of any particular compound of cement, nor confine myself to any formula, a sealing compound is preferable consisting of extremely fine 50 ground cement of a clay or rock base, thoroughly waterproofed in the manufacture, and the crushing strength of which is approximately two hundred pounds to the square inch when thoroughly set. Such a 55 composition for instance, of the consistency of heavy cream may be poured into the mortise-groove m , shown in the first three figures of the drawings, until the level indicated by the line $x-x$ (Fig. 2), is attained, 60 or even above the plane of that line, as any excess will simply be made to exude through the joint during the sealing operation. The cover C , being then properly positioned and alined above the casket body B , and lowered, 65 the protrusion of the coupling tenon

c, c' , into the mortise-channel m , owing to the fluid condition of the cement s , displaces the surplus or excess of cement and forces a sufficient quantity of it into any and all spaces and interstices between the opposed 70 contactual surfaces of the lid and casket rim to expel all air and completely fill all spaces that would otherwise be void, thus hermetically sealing the joint as soon as the sealing compound sets and hardens. 75

It will thus be seen that I attain automatically locking and hermetically sealing means of great simplicity and effectiveness, and that the locking and sealing are accomplished simultaneously in one operation, 80 *i. e.*, that of simply positioning the lid on the casket after the sealing compound has been introduced into the mortise-groove in the rim of the latter. Furthermore the operation is so simple and the registration of 85 parts necessarily so true owing to the overlapping flange c'' , on the outer edge of the lid C , that skilled labor is not essential to its successful performance; and all screws, bolts, or other extraneous securing devices 90 are entirely dispensed with. Thus the casket may be designated as "self-contained" in so far as the locking and sealing means are concerned, because they are internal and are rendered inaccessible by the mere act of 95 applying the lid to the casket body, so that reopening of the casket by the removal of the lid is rendered practically impossible. The seal is both air and water tight and 100 will remain so perpetually.

What I claim as my invention and desire to secure by Letters Patent is,

1. In combination with a casket of the character designated, means for automatically locking and hermetically closing the same, comprising the rim of the casket body formed with a circumscribing mortise-groove, the opening into said mortise-groove being of less width than that of the cross section of the groove below said opening, a coincident coupling tenon on the lid of less width than said opening to the mortise-groove in the body rim of the casket, the shank of said coupling being of less thickness than a lower portion thereof, a centralizing register flange on the lid engaging the inner and outer walls of the rim of the casket and positioning the said coupling tenon with relation to said mortise groove in the rim of the casket, and an air- and water-proof sealing compound interposed between the said parts, whereby the coupling tenon on the lid is positively and rigidly embedded and anchored with the hardened sealing compound in the mortise-groove in the rim of the casket body and the joint is hermetically sealed, for the purpose described. 110

2. A casket having its body portion formed with a circumscribing mortise groove 130

opening through the top of the rim with a flange and rim being correspondingly beveled, and a hardening sealing material in said groove, surrounding said tenon and flange and filling the groove and the space 15 between the opposed contactual surfaces of said lid and rim.

5 than the width of said mouth, said lid being formed with an external circumscribing register flange fitting said rim and centralizing the coupling tenon with its coupling flange to the mortise groove and embracing the

10 rim snugly upon both of its inner and outer walls, the outer contacting faces of said
